(57) **CLAIM**

The ornamental design for an inflator with removable light, as shown and described.

DESCRIPTION

FIG. 1 is a perspective view of the inflator with removable light, according to one embodiment of this invention;

FIG. 2 is a front view of the inflator with removable light shown in FIG. 1;

FIG. 3 is a rear view of the inflator with removable light shown in FIG. 1;

FIG. 4 is a side view of the inflator with removable light shown in FIG. 1;

FIG. 5 is a side view, opposite the side view shown in FIG. 4, of the inflator with removable light shown in FIG. 1;

FIG. 6 is a top view of the inflator with removable light shown in FIG. 1;

FIG. 7 is a bottom view of inflator with removable light shown in FIG. 1; and,

FIG. 8 is a perspective view of the inflator with removable light shown in FIG. 1 with a light in a removed position.
